UNITED STATES PATENT OFFICE.

JOHN E. WOODBURY, OF WORCESTER, MASSACHUSETTS.

COUNTER FOR INTAGLIO-PRESSES.

1,255,263.

Specification of Letters Patent. Patented Feb. 5, 1918.

Application filed July 17, 1913. Serial No. 779,451.

To all whom it may concern:

Be it known that I, JOHN E. WOODBURY, a citizen of the United States, residing at Worcester, in the county of Worcester and 5 State of Massachusetts, have invented a new and useful Counter for Intaglio-Presses, of which the following is a specification.

This invention relates to intaglio printing. It is especially made for the purpose of 10 facilitating printing from intaglio plates on moistened paper. In practice, I have found that when printing on moistened paper from intaglio plates, containing both 15 illustrations and reading matter, it is difficult to remove the paper from the ordinary counter with sufficient rapidity to do commercial printing. If a blanket is provided as a part 20 of the counter for the purpose of overcoming this difficulty, it is subject to additional difficulties owing to the fact that the broad cuts in the intaglio plate, especially those forming the letters, will receive continually increasing 25 projections from the soft blanket as the same is compacted. This tends increasingly to cause the ink to be forced out at the edges of the cuts and to make bad work.

One of the objects of this invention is to provide for remedying this difficulty and especially to provide means whereby the operator can control the operation of the remedying means in accordance with the conditions existing. Another object of the invention is to provide for preventing the additional part of the counter which is used from 35 getting out of the register. The invention also involves improvements in details of construction of mechanism for printing. Further objects of the invention will appear hereinafter.

Reference is to be had to the accompanying drawings in which—

Figure 1 is a side view of a plate printing press showing a preferred embodiment of this invention applied thereto;

Fig. 2 is a front elevation of the same;

Fig. 3 is a side view of a portion thereof on enlarged scale;

Fig. 4 is a front elevation of the counter on a larger scale than that shown in Fig. 2.

Fig. 5 is a horizontal sectional view on the line 5—5 of Fig. 4.

Fig. 6 is a plan of a modified construction, and

Fig. 7 is a similar view showing the parts 55 in a different position.

The invention is shown as applied to a well known type of intaglio press having a frame 10, driving shaft 11, and feed mechanism 12 for driving a roll 13 which moves a web of paper along for wiping off the plate. This 60 press also as usual is provided with a counter support 15, and a plunger 16, details of which will not be described as they do not constitute a part of this invention.

On the counter support is the usual counter block 20 carrying the counter 19, but in addition to this ordinary construction it is provided with a second portion 21 which forms a part of the counter, and is movably mounted with respect to the main part thereof. This is shown as consisting of a blanket or the like formed of suitable blanket material. It is shown as being mounted on a rectangular frame 22 which surrounds the counter. This is provided with integral 75 guides 23 extending inwardly and engaging the longitudinal edges of the main counter block for a purpose to be described in full hereinafter.

This blanket is connected with the frame 80 by clamps 24 which are held by bolts.

The blanket and blanket frame are held normally toward one side of the press by a spring 25, which in this case is shown as also supporting the end of this frame. The 85 tendency of the spring is to force the counter frame to the right in Figs. 2 and 4.

Connected with the other end of the frame is a rod 26 which is pivoted on a crank 27 on a vertical shaft mounted in a bearing 28 on 90 the frame. This shaft is provided with an arm 29 for operating it. The arms 27 and 29 and the shaft can be made conveniently of an integral piece of wire bent into the shape shown. The arm 29 is intended to be operated by a link 30 which is provided with a stud 31 connected by a link 32 with a crank 33 pivoted on a bracket 34 on the frame. By operating this crank the link and consequently the stud 31 can be raised and lowered.

Mounted on the frame is a stationary plate 35 having a V-shaped slot 36 provided with a socket 37 at the top. Pivoted to this plate on a pivot 39 is a swinging plate 40. This 105 swinging plate has a slot 41, the bottom of which is just wide enough to receive the stud 31 and the top extends as high as the socket 37, which also is just large enough to receive the stud. This plate 40 is connected by a 110

link 42 with an eccentric 43 on the shaft of the roll 13.

The operation of this part of the device is as follows: When the stud 31 is at the bottom 5 of the slot 41, the oscillation of the link 42 causes the plate 40 to oscillate and the link 30 to partake of this motion. This obviously swings the arms 29 and 27 vibrates the rod 26 and the blanket 21 between impressions. 10 If, however, the crank 33 is turned to such a position that the stud 31 is held up in the notch 37 it is freed from the control of the slot 41 and positively prevented from vibrating, although the plate 40 continues to operate as usual. 15

The purpose of this mechanism is to control fully the condition of the blanket and consequently the printing. With the parts in stationary position, it is obvious that the 20 blanket will gradually become harder on the compressed portions but not in the portions which do not come into contact with the plate but only into the engraved lines thereon. When this action continues to such an 25 extent as to force the ink out of the engraved lines and blur it around the edges the operator will simply move the crank 33 so as to bring the stud 31 down into the bottom of the slot 41 and then the blanket 30 will vibrate and receive impressions on different portions of these surfaces. This will 35 tend to produce a uniform condition of the blanket and then the operator can swing the crank 33 back and allow the printing operation to go ahead with the blanket in its original position until the same condition is met with again. When this shifting action first takes place some of the first impressions may not be perfect and it is only 40 after the result has reached a sufficiently high degree of perfection that the parts are secured in inoperative position so as to continue that character of printing.

It will be observed that the vibrations of 45 the surface of the counter, namely the blanket 21, will be caused to be absolutely rectilinear on account of the guides 23 on frame 22 which engage the edges of the counter block 20. In this way the tendency 50 which the blanket has to shift about laterally is entirely obviated, and the blanket can be brought back exactly to its original position, so that the compression previously obtained need not all be lost. Thus good 55 printing can be done without material waste of time, and the life of the blanket is not lessened.

Another form in which the invention can be carried out is indicated in Figs. 6 and 60 7. In this case the numerals 10 and 26 indicate the same elements as in the other case. It is to be understood that the rod 26 is connected with a construction like that shown in Figs. 4 and 5, with or without 65 modifications. This rod 26 in this case is

pivoted to a bell crank having two arms 50 and 51. These two arms if desired can be secured to opposite ends of a shaft 52. The arm 51 is provided with two notches 53 and 54.

Mounted in convenient position is a pivoted plate 55 adapted to come against either one of two stops 56 or 57 and it is provided with a pivot 58 which is connected by a link 59 with a member 60 on the arm of a controlling rod 61. This rod is designed to be operated from the eccentric 43 shown in the other figures. The connection between the members 59 and 60 has a projecting pivot stud 62 at the point of connection.

In the position shown in Fig. 6 the spring on the right hand end of the blanket tends to hold the rod 26 and consequently the arm 50 to the right and to hold the arm 51 forward. Consequently the vibration of the 85 rod 61 has no tendency to dislodge the pin 58 from the notch 54 in which it is located. Therefore, when it is desired to prevent vibration of the blanket the plate 55 is brought to the left into contact with the stop 56. 90 When it is desired to cause the blanket to vibrate, the plate 55 is moved to the right into contact with the stop 57 and the notch 54 engages the stud 62. In this case the vibration of the rod 61 causes the arms 50 95 and 51 to vibrate as will be obvious.

Another way in which the device can be used is for the operator to move the plate 55 over so that the other notch 53 engages the pin 58. This simply moves the blanket over to a second position by slightly raising the arm 51 and it is held there until the operator changes it. This arrangement is provided so that the operator can move the blanket over if in his judgment it needs it 105 either with or without the accompanying vibration thereof.

It has been found in practice that by the use of this invention either in the forms shown, or in other forms for accomplishing 110 the same purpose the counter can be kept, by a comparatively unskilled operator, in proper condition for the highest class of printing of this difficult type, namely, the printing of both illustrations and reading 115 matter from the same engraved plate and that the moistening of the paper which has also been found to be necessary does not introduce any complications that are not overcome by this invention.

While I have described my invention in connection with the production of work of the above character, upon moistened paper, the invention presents valuable advantages when employed in the production of certain kinds of ordinary die stamping upon dry paper and I do not wish to be limited to the use of my invention on any particular class of intaglio work.

Although I have illustrated and described 130

only two forms of the invention I am aware of the fact that it is capable of being carried out in many other ways without departing from the scope thereof as expressed

5 in the claims, therefore, I do not wish to be limited to the forms shown and described but what I do claim is:—

1. In an intaglio printing press, the combination with a counter made in two parts, 10 one consisting of a soft blanket, of means for reciprocating one of said parts relatively to the other part.

2. In an intaglio printing press, the combination with a counter made in two parts, 15 a main part and a movable face, of means for vibrating said face short distances along the main part of the counter.

3. In an intaglio printing press, the combination with a counter made in two parts, 20 a main part and a movable face, of means for moving said face along the main part of the counter a distance less than the length of said main portion, said means being movable to inoperative position on the press.

25 4. In an intaglio printing press the combination of a counter having a relatively movable face, of means for periodically vibrating said face back and forth in a plane parallel to the operative face of the counter 30 and means for rendering the vibrating means inoperative.

35 5. In an intaglio printing press the combination of a counter having a relatively movable face, of an eccentric operated by the press, a member connected with said eccentric to be vibrated thereby and means whereby the movable face of the counter can be operatively connected with and disconnected from said movable member.

40 6. In an intaglio printing press the combination of a counter, a frame adjacent to the counter, a blanket carried by said frame and constituting the face of the counter and means for vibrating said frame parallel 45 with the face of the counter.

7. In an intaglio printing press the combination of a counter block supporting a counter, with a frame surrounding the counter and having means for engaging two opposite 50 sides of the counter block for guiding the frame parallel with the counter, a blanket supported by said frame and pass-

ing over the operative face of the counter and constituting a part thereof, and means for vibrating said frame longitudinally of 55 the counter.

8. In an intaglio printing press, the combination of a counter block supporting a counter, a frame surrounding the counter and engaging the counter block on opposite 60 sides thereof whereby the frame is guided by the counter block longitudinally thereof, a blanket secured to said frame and engaging the operative face of the counter, a spring for normally holding said frame at 65 one end of the counter, and means for reciprocating the frame in opposition to the spring.

9. In an intaglio printing press, the combination of a counter having a movable 70 face, means for vibrating said movable face, means for holding the movable face stationary in one position and means for holding the movable face stationary in a second position.

75 10. In an intaglio printing press, the combination of a counter having a movable face, an arm connected with said movable face for operating it, a pivoted member having a stud thereon, said arm having two notches 80 for receiving said stud, and a vibrating member having a stud thereon and adapted to engage in either of said notches and connected with said pivoted member.

11. In an intaglio printing press, the combination of a counter having a movable face, means for holding the movable face stationary in one position and means for holding the movable face stationary in a second position.

85 12. In an intaglio printing press, the combination of a counter made in two parts, means by which one part can be moved relatively to the other, and means for bringing said parts back into their original positions.

90 In testimony whereof I have hereunto set my hand, in the presence of two subscribing witnesses.

JOHN E. WOODBURY.
